UNITED STATES PATENT OFFICE.

EDWARD T. MOORE, OF WEST PHILADELPHIA, PENNSYLVANIA, ASSIGNOR OF ONE-HALF TO RICHARD ALLEN, OF PHILADELPHIA, PENNSYLVANIA.

STEAM-BOILER FURNACE.

Application filed October 27, 1921. Serial No. 510,716.

The object of the invention is to provide an efficient construction of steam boiler and furnace having improved means for insuring a proper circulation of the products of combustion under such conditions as to utilize most effectively and economically the heat produced by the consumption of the fuel, and also to provide a construction which will have increased stability and strength to resist the pressures to which the same is subjected while affording ample means for removing accumulations of soot and ashes from the parts thereof so as to maintain the maximum efficiency at all times; and with these objects in view the invention consists in the construction and combination of parts of which a preferred embodiment is shown in the accompanying drawings, wherein:

Figure 1 is a longitudinal vertical sectional view of a structure embodying the invention.

Figure 2 is a transverse sectional view on the plane indicated by the line 2—2 of Figure 1.

Figure 3 is a similar sectional view on the plane indicated by the line 3—3 of Figure 1.

Figure 4 is a front view of a portion of the structure showing a part of the refractory lining thereof.

Figure 5 is an inverted plan view of the boiler alone.

Figures 6 and 7 are detailed sectional views on the planes indicated by the lines 6—6 and 7—7 of Figure 1.

The boiler consists essentially of an outer shell or wall 10 and an inner shell or wall 11 of which the latter is arched to form a combustion chamber 12 spanning and extending rearwardly from the fire box 13, the side portions of the inner wall being disposed in downwardly convergent relation with the lower portions of the outer wall or shell to form downwardly contracted longitudinal pockets 14 extending longitudinally of the structure, said walls being riveted or otherwise effectively secured to longitudinal base bars 15 resting upon the base plate 17 from which extend downward the angle supports 18 within which and reinforced by which is arranged the masonry 20 forming the wall of the furnace proper which includes the above indicated fire box 13, an ash pit 19, a bridge

wall 20, and a soot pocket or pit 21 located 55 in rear of the bridge wall.

In the front wall of the furnace proper there is arranged the usual fuel door 22 and ash door 23 respectively above and below the plane of the grate 24.

The upper portion of the exterior shell or wall of the boiler is preferably arched as indicated at 25 and is interiorly braced transversely by plates 26 while intermediate the side walls of the exterior shell are 65 connected by transverse braces 27, and extending from said exterior side walls to the inner shell or wall are braces 28 which add to the rigidity of the structure, the attachment of said bracing elements to the walls 70 of the shells being effected, for example, as shown, by means of angle bars 29 or the equivalent thereof. Secured terminally in

the front and rear walls 30 and 31 of the boiler are the upper and lower sets of fire 75 tubes 32 and 33, suitable tie rods 34 and 35 also extending between said front and rear plates, and communicating with the rear ends respectively of said upper and lower

series of fire tubes are the stack 36 provided 80 with a suitable damper 37 and the smoke flue 38 which communicates with the rear end of the combustion chamber, suitable openings 39, 40 and 41 being arranged

respectively in alignment with the upper 85 and lower sets of fire tubes and the combustion chamber, at the rear ends thereof and being fitted respectively with movable covers 42, 43 and 44. The rear wall is preferably provided with a refractory lining 45 in 90 which the smoke flue 38 is formed, said lining extending upward beyond the plane of the lower series of fire tubes to a head plate 46 which separates the upper end of the smoke flue from the stack.

At their front ends the upper and lower sets or series of fire tubes communicate with a smoke box 47 fitted with a closure 48 which is common to both sets of flues and gives access thereto for cleaning purposes 100 in conjunction with the man hole covers at the rear ends of said flues.

The boiler is preferably equipped at its top with a steam gage 49, a water gage 50, suitable outlet pipes 51 and 52 respectively 105 for steam circulation and safety valve attachment, and also if desired with an outlet 53 by which connection may be made with

an injector pump or the like. Also a man hole fitted with a suitable cover, may, as indicated at 54 be arranged near the rear wall of the boiler in the arch forming the top thereof.

The combustion chamber is spanned transversely by front, intermediate and rear drums 55, 56 and 57 terminally secured to the walls of the inner shell 11 and in communication by means of openings 58 in said shell with the pockets 14, so as to provide for a transverse circulation of water between said pockets and through the combustion chamber, the front and rear drums being disposed in pendent relation with the boiler with their lower ends exposed and constituting downwardly deflecting baffles for the products of combustion, while the intermediate drum is preferably mounted upon and forms an extension or continuation of the bridge wall to cause the products of combustion on leaving the fire box to pass over said intermediate or bridge wall drum and thence pursue a downward and rearward course to pass under the rear pendent drum 57 before entering the smoke flue 38. These drums obviously constitute effective means for communicating the heat of the combustion chamber to the contents of the boiler so as to effect an economy in the use of the fuel and extract the maximum of heat units from the products of combustion before they can reach the outlet after which as will be understood from the foregoing description the said products of combustion pass first forwardly through the flues of the lower set 32 and into the smoke box 47 and thence rearwardly through the flues 32 to the stack.

Communicating with the longitudinal side pockets of the boiler and in alignment respectively with the transverse drums are the clean-out pipes 59 fitted if preferred with gate valves 60 and serving as means for removing any sediment which may accumulate in the drums. The front wall of the com-

bustion chamber may consist as shown of a refractory brick structure 61 extending upward to the bottom plate 62 of the smoke box 47.

Having thus described the invention, what I claim is:—

1. A boiler furnace having a boiler, a fire box, fire tubes passing through said boiler and leading to a discharge flue, the apparatus having an outlet passage leading from the fire box for products of combustion, a smoke flue leading from said passage to said tubes, baffles in communication with the water space of the boiler, means mounting the boiler and supporting one of said baffles in said passageway, another of said baffles depending into said passageway between the smoke flue and the last mentioned baffle and providing between the same and said means a restricted outlet for the products of combustion to facilitate precipitation of solid matter therefrom, and a soot pocket provided in said means located adjacent the lower end of the depending baffle. 70

2. A boiler having an outer shell, an arched inner shell, said shells being spaced apart at their side walls to constitute pockets, the inner shell constituting a combustion chamber, means providing a fire box 75 in communication with the combustion chamber, supporting means for the shell enclosing the fire box having a bridge wall and a soot pocket in the rear thereof, a baffle member spanning the inner shell and communicating with said pocket and resting on said bridge wall, a baffle member depending from the inner shell spanning the latter and communicating with said pocket, the last mentioned baffle extending relatively close 80 to said means adjacent the rear extremity of the pocket to provide a restricted space to facilitate precipitation of solid matter from products of combustion. 85

In testimony whereof I affix my signature.

EDWARD T. MOORE.
